UNITED STATES PATENT OFFICE.

HERMAN GRUNOW, OF DETROIT, MICHIGAN.

CALENDAR.

Application filed August 1, 1927. Serial No. 209,709.

My invention relates to a new and useful improvement in a calendar so arranged that it may be used to determine the dates of the days of the month for practically any year 5 by simply adjusting a movable part to the proper position on the supporting member.

It is an object of the present invention to provide a calendar of this class which will be simple in structure, durable in use, adapted for quickly determining the dates over 10 long periods of time, and one which may be easily and quickly operated and adjusted to its various positions.

Another object of the invention is the provision of a perpetual calendar of this class arranged on a basis of twenty-eight years and so constructed as to provide for the additional days of the leap years.

Other objects will appear hereinafter. 20 The invention consists in the combination and arrangement of parts hereinafter described and claimed.

The invention will be best understood by a reference to the accompanying drawings 25 which form a part of this specification and in which,

Fig. 1 is a front plan view of the invention showing the supporting member in fragment.

Fig. 2 is a view similar to Fig. 1 with the 30 movable part removed.

Fig. 3 is a sectional view taken on substantially line 3—3 of Fig. 1.

Fig. 4 is a view taken on line 4—4 of 35 Fig. 1.

In the drawings I have illustrated the invention which comprises a supporting member 7 made from card board or other suitable material. Extending vertically of this supporting member are the guide members 8 and 9 which, as shown in Fig. 3, extend through the member 7 and are formed T shaped, the guide strips 8 and 9 being spaced outwardly from the outer face of the supporting member 7. Appearing at one side of 45 the supporting member are columns 10 above which appears a column 10' to indicate the nature of the display which is mounted in the columns 10, each of these columns 10 being divided into a plurality of squares or 50 sections. At the opposite side of the supporting member 7 appears a column 11 which is divided into a plurality of squares or sections, and above which appears the indicating square 11' to indicate the nature of 55 the display in the column 11. Positioned be-

tween the columns 10 and 11, and preferably equally spaced therefrom at the sides are a plurality of columns 12, each divided into a plurality of sections or squares, and positioned above the column 12 is the indicating space 12' wherein is displayed data indicating the nature of the display in the columns 12.

The calendar is based on a period of 65 twenty-eight years and in the columns 10 appear the last two numbers of the years. In the column 11 are similarly displayed the last two numbers of the years which are leap years, the numbers of the years displayed in the columns 10 and 11 covering a period of twenty-eight years extending in a particular arrangement shown from 21 to 48, the column 11 displaying the numbers of the years over those intervals which are not 75 displayed in the columns 10.

In the columns 12 are displayed the numbers corresponding to the numbers of the days of the month in an arrangement co-ordinated with the arrangement of the years 80 displayed in the columns 10 and 11.

A slideable member is adapted for mounting on the supporting member 7, being retained in position by the guide strips 8 and 9, this slideable member comprising a card 85 board 13 having openings 14, 15 and 16 formed therein, the opening 14 being so arranged that when the card 13 is mounted in position on the supporting member 7, this opening will register, as the card is moved 90 vertically of the supporting member 7, with the columns 12 and frame a certain portion of these columns 12. The opening 15 is so arranged on the card as to register with the columns 10 so that when the card 13 is moved vertically on the support 7, this opening 15 will serve to frame a certain portion or all of the columns 10, depending upon the position of the card 13 on the supporting member 7.

Similarly the opening 16 is adapted to register with the columns 11 and serve to frame a portion or all of the column 11 depending upon the position of the card 13 relatively to the support 7. The portion 17 105 of the card which is positioned between the openings 15 and 16 is adapted for the display of the names of the days of the week and upon movement of the card 13 vertically on the support 7 is adapted to cover the space between the edges of the columns 12 and 10. Similarly the portion 18 of the card 110

13 lying between the openings 14 and 16 serves to display the names of the days of the week and to cover the space between the column 11 and the edge of the columns 12.

5 At one side of the card is the portion 19 in which is displayed the names of the months of the year, and at the opposite side of the card is the portion 20 in which is displayed the names of the months of the year.

10 In operation the card 13 is moved to the position in which the month under consideration registers with the column in which the year appears. For instance, if it is desired to know the days of the week on which 15 the various dates in the month of June 1923 appeared, the card 13 would be moved to the position shown in Fig. 1, and the space or opening 14 would frame the numbers registering with the proper week day names to 20 correspond to the month and year in question. Should it be desired to ascertain the dates of a certain month in 1954, since our display matter extends to the year 1948, it would be necessary to subtract 28 from the 25 year 1954 which would give the year 1926. Consequently in order to know the dates of the month of April 1954, the card 13 would be moved to the position shown in Fig. 1 in which the month of April registers with the 30 numeral 26 displayed in the columns 10, the opening 14 serving to frame the numerals in the columns corresponding thereto, these numerals being in proper registration with the display matter in the column 17 or the column 35 18.

Should it be desired to ascertain the dates of the year 1944 for the month of June, the card 13 would be moved to the position shown in Fig. 1, the month of June appearing 40 in the column 20 being in registration with the numeral 44 appearing in the column 11, the opening 14 serving to frame the proper numbers displayed in the columns 12 which are in registration with the proper 45 day of the week.

Should it be desired to use the calendar for a date prior to 1900, the calendar will indicate one day early owing to the fact that 1900 was not a leap year. Consequently, if 50 the calendar should show the date appearing on Sunday it actually would appear on Monday for all dates prior to 1900 or during the 19th century.

Consequently, it is seen that I have provided 55 a calendar which on its face will perpetually indicate all dates of the various months showing the day of the week for the

period of time extending from March 1st 1900 until February 28th 2100.

While I have illustrated and described the 60 preferred form of my invention, I do not wish to limit myself to the precise details of structure shown, but desire to avail myself of such variations and modifications as come within the scope of the appended claims. 65

Having thus described my invention what I claim as new and desire to secure by Letters Patent is:

1. A century calendar of the class described comprising: a supporting member 70 having numerals in columns at one side thereon indicating years, and numerals displayed at the opposite side thereof indicating years, said indicating numerals covering a period of twenty-eight years, the numerals at one 75 side of said supporting member indicating the leap years, said member having displayed, intermediate said numerals, data indicating the number of the days of the month; a movable frame forming member movable on said supporting member and provided with openings for framing in its various positions of movement a portion of said day indicating data to include the days of a single month, said movable member having data displayed thereon for registering with said day indicating data so framed to indicate the day of the week corresponding to the date of the month framed; and month indicating data on said movable member to register with a portion of said year indicating data frame by said movable member for indicating the month framed by the day framing portion of said movable part. 80

2. A calendar of the class described comprising: a supporting member having at opposite sides columns of year indicating data covering a period of twenty-eight years, the data at one side relating solely to the leap years; and day indicating data displayed on said member, intermediate said year indicating data columns; a movable member mounted on said supporting member having openings formed therein to frame a certain portion of said day indicating data and said year indicating data, said movable member having displayed thereon data indicating the days of the week and the months of the year arranged to correspond with the year indicating data and the day indicating data 105 framed by said movable member. 110

In testimony whereof I have signed the foregoing specification.

HERMAN GRUNOW.
